AIR STARTING ARRANGEMENT FOR SWASH PLATE DIESEL ENGINES

Frank S. Strite, New York, N. Y.

Application November 26, 1946, Serial No. 712,417

7 Claims. (Cl. 60—16)

1

This invention relates to a power generating unit and has relation more particularly to a unit of this kind of the Diesel type, and it is a particular object of the invention to provide a unit of this kind including a rotor embodying a hollow shaft through which the required fuel is carried and which also provides means for the necessary exhaust and for the water cooling circulation.

The present application is a continuation in part of application Serial No. 494,255 filed July 10, 1943, now abandoned.

The invention also has for an object to provide a power unit of this kind which is of compact and condensed design, of perfect balance and non-pulsating, which eliminates the use of a fly wheel, and which assures effective conversion of thermodynamic heat into power.

The invention has for a further object to provide a power unit of this kind embodying actuating fuel oil spray valves and starting air valves, together with means for assuring the proper operation of such valves and also whereby the operation of the fuel spray valves may be readily advanced or retarded as desired.

The invention has for a still further object to provide a power unit of this kind including a rotor which can be employed to advantage as a power take-off or which can be employed to equal advantage as an electric generator rotor.

It is an additional object of the invention to provide a power unit of this kind comprising a stator including an oscillator disk operatively connected with a series of pistons in a manner whereby the reciprocation of said pistons effects the desired operation of the rotor.

The invention has for a still further object to provide a power unit wherein the rotor is of such design as to act as a fly wheel and wherein the assembly of the unit is such as to prevent a "dead center."

The invention consists in the details of construction and in the combination and arrangement of the several parts of my improved power generating unit whereby certain important advantages are attained, as will be hereinafter more fully set forth.

In order that my invention may be better understood, I will now proceed to describe the same with reference to the accompanying drawings, wherein:

2

Figure 1 is a view in side elevation of a power unit constructed in accordance with an embodiment of my invention.

Figure 2 is a view, partly in side elevation and partly in section and of a diagrammatic character, particularly illustrating the rotor and its associated parts when viewed from one side.

Figure 3 is a view, partly in elevation and partly in section and of a diagrammatic character, of the rotor block and the manifolds associated therewith.

Figure 4 is an enlarged fragmentary view, partly in section and partly in elevation, of one end portion of the unit as illustrated in Figure 1.

Figure 5 is an enlarged fragmentary view, partly in section and partly in elevation, of the opposite end portion of the unit as illustrated in Figure 1.

Figure 6 is an enlarged fragmentary view, partly in section and partly in elevation, illustrating in detail certain structural features of the air, oil and water circulating lines as herein comprised.

Figure 7 is a detail sectional view of an air intake funnel.

Figure 8 is an enlarged detailed view, partly in elevation and partly in section, of the adjustable trip contact and starting air contact arm as herein comprised.

Figure 9 is a view, partly in top plan and partly in section, of the structure illustrated in Figure 8.

Figure 10 is a fragmentary detailed sectional view taken lengthwise through a portion of a jacketed water pipe herein embodied.

Figure 11 is an enlarged fragmentary detailed sectional view taken substantially on the line 11—11 of Figure 4.

Figure 12 is a detail section taken substantially on the line 12—12 of Figure 4.

As illustrated in the accompanying drawings, F denotes a foundation or base plate of desired dimensions and which is provided with the upper standing heavy spaced blocks 1 and 2 provided respectively with the oil chambers 3 and 4 each having in communication therewith a pipe line 5 for communication with a suitable suction pump (not shown). The block 1 at its inner side is provided with an upstanding pedestal 6 which is aligned with an upstanding pedestal 7 carried by the inner portion of the second block 2.

Rotatably disposed through the pedestals 6 and 7 are the reduced end portions 8 of a hollow shaft S. This shaft S is of a length to bridge the space

between the pedestals 6 and 7 and extend outwardly therebeyond and beyond the blocks 1 and 2 a desired distance. The reduced portions 8 provide the shoulders 9 for coaction with the shoulders 10 within the adjacent end portions of the openings 11 in the pedestals 6 and 7 through which the reduced portions 8 of the shaft S are directed.

These shoulders 9 and 10 coact to prevent undue endwise movement of the shaft S although, of course, other means may be provided. The major portion of each of the openings 11 is enlarged to receive a roller bearing unit 12 so that the shaft S will rotate with a minimum of frictional resistance. Each of the units 12 is held in place by an annular member 14 bolted, as at 15, or otherwise secured to the outer face of a pedestal 6 or 7.

At a desired point between the pedestals 6 and 7 the shaft S has mounted thereon for rotation therewith a rotor block R of requisite dimensions and cylindrical in form and which is provided in its outer portion at points spaced equidistantly therearound with the openings 16 in each of which is tightly fitted a cylinder 17 open at both ends and which extends entirely through the rotor block R. The bores of the cylinders 17 are of the same radii and have their axial centers equally spaced from the axial center of the shaft S upon which the block R is fixed.

At the same side of the block R the cylinders 17 are closed by the heads 18, the peripheral portions of which are bolted, as at 19, or otherwise securely but detachably connected to the block R and each of these heads 18 at its axial center is provided with a fuel inlet opening or port 20 and to one side of such port 20 the head 18 is provided with an air inlet opening or port 21.

In close proximity to the block R at the side thereof carrying the heads 18 but spaced therefrom and surrounding and fixed to the shaft S, is a collar 22 provided with the outstanding and radially disposed spider arms 23 to the outer extremities of which is fixed an annular air manifold 24. This manifold 24 has in communication therewith a pipe line 25 which extends within the shaft S through a suitably positioned opening 26 and then extends outwardly and substantially axially of said shaft to a point beyond the end of the shaft and opens within an air chest 27. This air chest 27 is in communication through the pipe line 28 with a source of starting air under desired pressure.

Delivering within each of the cylinders 17 through the opening or port 21 of each of the heads 18 is an air delivering line 29 in communication with the manifold 24. Flow of air from the manifold 24 to a cylinder 17 through the line 29 is under control of the normally closed and inwardly opening valve 30 which is of the same construction as the hereinafter referred to valve 37 shown in detail in Figure 11, said valve 30 having a stem 31 extending outwardly of the line 29 with its outer end carrying a roller 32 for coaction with a starting contact arm 33 to be herein-after more particularly referred to. Interposed in the air delivering line 29 is a conventional check or a non-return valve 29' to prevent back flow of air and gases into the starting system.

The manifold 24 has disposed therearound and substantially concentric therewith a fuel oil manifold 34 herein disclosed as maintained in applied position through the medium of the interposed arms 35 (Figure 3) rigidly secured to both of the manifolds 24 and 34.

Each of the cylinders 17 has delivering therein

through the fuel inlet or port 20 a fuel line leading from the manifold 34 and flow through the line 36 into this cylinder 17 is under the control of the inwardly opening valve 37 having a stem 38 extending outwardly of the line 36 and having its extended extremity carrying a roller 39 for coaction with an adjustable trip block 40 (Figure 9) forming a part of a trip unit T, to be more particularly described hereinafter.

The manifold 34 has delivering thereto an oil line 41 extending within the shaft S through a suitably positioned opening 42 and leading from a fuel pipe 43 surrounding the pipe line 25 but spaced therefrom. This pipe 43 opens within an oil chest 44 which is separated from the air chest 27 by a dividing plate 45 through which the pipe line 25 passes, as at 46. The chests 27 and 44 are within a common housing 47, herein disclosed as bolted, as at 48, or otherwise releasably anchored, to the outer face of an outboard bearing member 49 bolted, as at 50, or otherwise secured to the outer face of a bearing stand 51.

This bearing stand 51 is mounted upon the block 1 outwardly of the pedestal 6 and has the shaft S disposed therethrough. The housing 47 is formed as at 52, to allow for the mounting therein, of any desired mechanism which may be operatively coupled with a gear 53 carried by an end portion of the shaft S extending within the chest 44. Such mechanism may be, for example, a fuel pump.

The housing 47 has delivering therein in desired position with respect to the pump a fuel oil supply line 47'.

The wall of the bore 55 through which the shaft S passes is provided with an annular channel 56 with which constantly communicates a port 51 in the shaft S. This channel 56 has in communication therewith a port 58 disposed through the outboard bearing 49 and which port 58 has in communication therewith a cooling water inlet line 59. The port 57 is in communication with a tubular water jacket 60 surrounding the major portion of the pipe 43 with its inner end terminating at a point within the rotor block R. The outer end of this jacket 60 is closed, as at 61, while its inner end is open and the space between the inner open end of the water jacket 60 and the wall of the bore of the shaft S is sealed, as at 62. It is also preferred that the wall of the jacket 60 be of an insulated type to increase the efficiency of the cooling system. The water jacket 60 may be insulated in any manner desired but it has been found advantageous to have the wall of such jacket comprise two surrounding and spaced tubular members X, as shown in detail in Figure 10 the intervening space having desired insulation X' therein.

Reciprocating in each of the cylinders 17 is a piston 63 with which is operatively connected the piston rod 64 which extends out and beyond the open end of the cylinder 17 remote from the head 18. This piston rod 64 has its outer portion operatively connected through a suitable joint, as at 65, with the marginal portion of an oscillatory disk 66 rotatably mounted upon an elongated stationary sleeve or tubular guide arm 67 surrounding the shaft S and having one end portion 67' anchored, as at 68, to the inner face of the pedestal 7 and to the block 2. The opposite end portion of the sleeve or guide arm 67 terminates inwardly of the bevel gear 70 carried by the rotor block R which is herein-after more particularly referred to. Within the hub portion of the disk 66 for coaction with the sleeve 67 is a roller bearing assembly 69.

The disk 66 is disposed radially on an angle less than 90 degrees with respect to the shaft S but on such an angle as to have an in-and-out travel during its swing equal in distance to a stroke of each of the pistons 63, so that power will be applied to the disk 66 on such an angle or cant as to prevent "dead center."

In the present embodiment of the invention, the cylinders 17 are eight in number and the pistons working therein are equidistantly spaced relative to the disk 66, thus assuring requisite power being imposed upon the disk 66 when the power generating unit is in operation. Diametrically opposed pistons 63 move in opposite directions and such opposed pistons 63 successively reach the ends of their stroke.

The face of the rotor block R opposed to the oscillatory disk 66 carries for rotation therewith a bevel gear 70 of desired radius and with which meshes an internal bevel gear 71 carried by the disk 66, so that the reciprocation of the pistons 63 in association with the disk 66 will effect the desired rotation of the rotor block R. As is clearly illustrated in the accompanying drawings, the gear 71, which may be termed the driver gear, is disposed radially on the same incline or cant with respect to the shaft S as the disk 66, and interposed between the rotor block R and the disk 66 and surrounding the adjacent inner portion of the sleeve or guide arm 67 is a thrust sleeve or bearing 72.

The sleeve or guide arm 67 outwardly of but closely adjacent to the disk 66 rigidly carries a surrounding guide plate or bracket 73 having a face 74 disposed radially on the same angle or cant as the disk 66 and carried by the inner face portion of this plate or bracket 73 are the rotor bearings 75 for coaction with the opposed face 76 of the disk 66. The sleeve or guide arm 67 is provided therethrough with an oil passageway 77 which delivers to the bearings 69, and also in communication with this passageway 77 is a lubricating oil line 78 which terminates above the path of travel of the operative connections 65 between the piston rods 64 with the disk 66 and discharges into a receiving cup 79 included in each of such connections 65.

The rotor block R is provided radially thereof in its inner portion with the exhaust passages 80 each of which is in communication, as at 81, within a cylinder 17 at a desired point intermediate its ends and with the interior of the shaft S through the openings 82 in said shaft. The shaft S to one side of such openings 82 has its bore closed by an intersecting septum or plate 83, so that the exhaust passing out from the cylinder 17 will enter the exhaust pipe 84 within and extending lengthwise of the shaft S through the end portion thereof remote from the pipe lines 25 and 43.

The inner end of this exhaust pipe 84 is open and the space between said open end of the pipe 84 and the wall of the bore of the shaft S is closed by the sealing member 85 surrounding said inner portion of the exhaust pipe 84. This exhaust pipe 84 is of an insulated or jacketed type and is of a length to have its outer end terminate within the shaft S at a desired point beyond the pedestal 7 of the block 2. This outer extremity of the pipe 84, as herein disclosed, is continued by a lateral portion 86 which passes through an opening 87 in the shaft S and has communication with an internal annular groove 88 in the bearing member 89, through which the shaft S is directed. This bearing member 89 is

suitably anchored upon the block 2. The annular groove 88 communicates with an exhaust outlet passage 89a with which an exhaust pipe 89b is connected.

The shaft S in the present embodiment of the invention extends outwardly beyond the block 2, said extended portion carrying a power take-off pulley 90, together with a flanged coupling 91, either of which is to be employed when desired. The block R inwardly of the cylinders 17 and to the side of the septum or plate 83 remote from the passages 80 is provided with the substantially U-shaped water circulating passages 92, one extremity of each passage being in communication through an opening 93 with the interior of the shaft S inwardly of the inner open end of the jacket 60 while the opposite extremity of each passage is in communication through the opening 94 within the shaft S in the space between the jacket 60 and the wall of the bore of the shaft S.

The shaft S at a point outwardly of the pedestal 6 is provided with an opening 95 in communication with the space between the jacket 60 and the wall of the bore of the shaft S and with an internal annular groove or channel 96 in the bearing stand 51. This channel or groove 96 has leading therefrom a port 97 continued by a return pipe line 98 for the water circulating system.

Housing the disk 66 and the parts immediately associated therewith, is a two-part, longitudinally divided bowl-like hood which is generally designated H. This hood, as clearly shown in Figures 1 and 4, has its marginal portion anchored, as at 99, to the adjacent face of the rotor block R for rotation therewith.

At its axial center the hood H is provided with an opening 100 to receive the sleeve or guide arm 67 as shown in Figure 5. This opening 100 is encircled upon the outer end of the hood by the axially directed collar 101, which collar is divided also as shown. By dividing the hood in this manner it may be conveniently placed in position to enclose the disk 66 and other parts.

The longitudinal edges of the two parts of the hood are bordered by the outwardly directed flanges 101' which are disposed in abutting relation when the two parts of the hood are assembled and are secured by suitable bolts 101''.

The outer portion of the collar 101 is of increased diameter to receive packing material 102 which is secured in place by the two-part annular gland nut 103, the parts of which nut are secured together by the transverse coupling bolts 103'.

The lower portion of the sleeve or guide arm 67 has formed therein a passageway 104 which has connected with its outer end a pipe line 105 designed for connection with an oil suction pump, not shown. The passageway 104 at its other end opens within the hood H and has connected therewith an end of a suction pipe 106 which has its other or intake end disposed in the lower part of the hood within the annular sum 106' which is formed in the body of the hood adjacent to the face of the rotor to which the hood is attached.

The rotor block R, outwardly of each of the cylinders 17 and upon the hood side of the block, is provided with an obliquely outwardly directed scavenger air inlet port 107 which has communication at 108 with the interior of the cylinder 17 at a point inwardly of and closely adjacent to the inner end of the piston in such cylinder when said piston is at substantially the end of its outward or power stroke, so that air may be intro-

duced into the cylinder in a suitable manner to scavenge the same.

While any suitable means may be employed for introducing air through the port 103 into each of the cylinders to scavenge the same when the piston therein is at the outermost limit of its stroke, a means is here shown comprising the connection in the outer end of each of the passages 107 of an air collector or funnel unit which is generally designated U and which has its inlet facing in the direction of rotation of the rotor so that air will be forced into and through the unit and into the adjacent cylinder immediately upon the uncovering of the port 108.

Each of the units U comprises an inner portion in the form of a threaded nipple 200, which is threaded into the outer end of the passage 107 and which at its outer end is encircled by the collar or flange 201. The nipple 200 has the central passage 202 therethrough which is enlarged at its outer end as indicated at 202' and within the outer end of the narrow part of the passage 202 are engaged the tapered vanes 203 which are integral with the underside of a valve disk 204. This valve disk 204 with a portion of the vanes 203, is disposed in the enlarged part 202' of the nipple passage to function in the manner hereinafter described.

The vanes 203 at their inner ends are attached to a spring 205 which in turn is secured to the inner end of the nipple in any suitable manner as, for example, by connection with the rod 206 which is disposed across the inner end of the passage 202. Thus the valve 204 is normally drawn inwardly and when in its inward position air may pass around the sides of the valve disk and between the vanes 203 to flow into the adjacent passage 107.

The second part of each air inlet unit comprises a funnel 207 which is of arcuate form as shown and at its smaller inner end it is provided with the encircling flange 208 which is positioned against the flange 201 to be secured thereto by the bolts 209.

The inner end of the passage 210 of the funnel is of a diameter materially less than the diameter of the portion 202' of the passage 202 and is concentric with such passage. Thus there is provided an annular shoulder or seat 211 which is spaced from and opposes the outer face of the valve disk 204. Against this seat the valve disk 204 is designed to position to close the outer end of the passage 202 if, for any reason, there should be a sudden back pressure developed in the cylinder when the piston is at the outer limit of its stroke. Thus the escape of exhaust through the air intake funnel would be prevented.

Within the passage 210 of the funnel is a regulating disk valve or damper 212 which is positioned upon the pivoted supporting rod 213 which passes diametrically through the funnel passage and at one end has a head 214 to facilitate manual adjustment of the damper.

The outer or large end of the air collecting funnel is preferably covered by a wire screen 215.

While the units U are mounted upon the rotating part or rotor R of the machine the valves 204 will not be closed by centrifugal force for the following reasons. At the end of the power stroke following the exhaust of the spent gases, air is admitted from the outside under pressure which is needed partly for assisting in expulsion of exhaust gases, scavenging and fresh air supply for compression and subsequent ignition. The air remaining in the cylinder after the exhaust port

10 closes, is subsequently compressed to several hundred pounds during the compression stroke with a corresponding temperature rise when reaching the end of the stroke, which is sufficient 15 to ignite fuel oil at its admission point. This admission with the attending combustion generates a gas pressure within the cylinder of several hundred pounds, causing the piston to move on its power stroke to a point where the exhaust port 10 20 21 is uncovered or opened, allowing the exhaust to escape to the atmosphere against 14.7 pounds pressure (at sea level). In engines of this type the mean effective pressure is around 60 pounds plus. As the exhaust leaves the pressure in the 15 cylinder will be rapidly reduced to a point where the valve 204 can, and will, be opened under the combined ram effect of the air scooped up by the moving funnels and the pull of the spring 205. Since the valves do not extend radially outwardly 20 of the rotating body but are directed tangentially to the axis of the rotation the centrifugal force to which they would be subjected would not be so great as would be the case if they were directed radially outwardly. Accordingly the 25 springs 205 which constantly tend to pull the valves inwardly to open position could be made of sufficient strength to overcome any tendency of the valves to close under the centrifugal force to which they are subjected when the machine is in operation.

This method of air supply gives a "super charging" effect similar to that used in airplane and other internal combustion engines and through outside mechanical means. This is needed for 30 operation at high altitudes and for better engine efficiency. In the present engine design the air supply is internal with the engine and the desired quantity can be obtained by adjustment of the regulating dampers 212 and the area of the port openings 108.

The peripheral face of the rotor block H is provided at spaced points therearound with the generator field pole pieces 109 for coaction with the generator armatures 110 surrounding the block R outwardly of the pole pieces 109 and which generator armatures 110 are carried by the supporting structure 111. Associated with the shaft S are the conventional field collecting rings 112.

It is not believed necessary to further describe or illustrate the details of the electrical generating assembly other than to state that as herein disclosed such assembly is of a type to generate alternating current although such assembly could be readily changed in a well known manner for the generation of direct current.

The contact arm 33 is substantially arcuate in form and is of such length and design, when starting air is used and the arm 33 is in effective position, as to assure a number of successive valves 30 being open, preferably four. With these valves 30 open, starting air will be admitted into the corresponding cylinders 17 to effect the initial power strokes of the pistons 63 and after the first or second revolution of the rotor block R, the acceleration and/or speed of the block R will be sufficient to cause the requisite ignition of the explosive charge, whereupon the contact arm 33 is swung into ineffective position and at which time the trip contact 40 is brought into position for contact by the rollers 39 of the fuel spray valves, whereby said valves will be caused to open successively in proper timed sequence with respect to the strokes of the pistons 63.

The trip unit T, as shown most clearly in Fig-

ures 8 and 9, comprises an elongated head 115 which is angular in cross section and which has the trip block 40 slidably mounted within a groove or channel 114 provided in the outer face of the elongated head or member 115 to one end portion of which an extremity of the contact arm 33 is rigidly secured and from which said arm 33 depends. The head or member 115 has threading through one end thereof, as at 116, into the groove or channel 114 an elongated shank 117, an end portion of which freely moves through an opening 118 in the opposite end portion of the head or member 115. This shank 117 is disposed lengthwise through and rotates in the trip block 40 and moves lengthwise therewith in the channel 114.

The cross sectional configuration of the trip block 40 and the corresponding cross sectional configuration of the groove or channel 114 is such as to hold the block 40 against turning or rotary movement upon the shank 117 yet allow said block 40 to freely move lengthwise of the groove or channel 114. In the present embodiment of the invention, this movement of the trip block 40 lengthwise of the groove or channel 114, with the endwise movement of the shank 117, is accomplished by providing the shank 117 with the spaced surrounding collars 119 in contact with the ends of the trip block 40.

This trip block 40 extends outwardly beyond the open face of the groove or channel 114 and said outer face has its opposite end portions *a* inwardly beveled and providing an intermediate straight contact face portion *b* of a length to assure a fuel spray valve 37 being maintained open for a desired period of time as the roller 29 passes over this trip block 40.

One end portion of the shank 117 is provided with a hand wheel 120 to provide means whereby the shank 117 may be rotated in a direction to selectively position the trip block 40 to advance or retard the opening of the valves 37 as may be desired. After the trip block 40 has been adjusted, it is maintained in such selected position by a binding screw 121, Figure 8, threading into the head or member 115 and having locking contact with the shank 117. It is to be noted that the contact arm 33 is entirely below the trip block 40 and is outwardly offset with respect to the head or member 115.

It is believed to be apparent that the advancing or retarding of the trip block 40 will determine the opening point of each of the fuel valves 37. This trip block 40 is provided on its face with the graduations 122 extending therealong to be used as an indicator of "timing" of injections and which graduations are employed in connection with an index 123 provided on the adjacent face of the head or member 115. By providing the trip block 40 with the beveled portions *a*, the contact of the rollers 39 therewith will be gentle or substantially shockless. As no special tripping is required for the air starting valves 30, the rollers 32 will contact the contact arm 33 throughout its length.

The member or head 115 closely adjacent to the end thereof from which the arm 33 depends is provided with a substantially perpendicularly related outstanding straight arm 124 and at the side of the member or head 115 remote from the arm 33. This arm 124 is pivotally connected, as at 125, to an upstanding bracket 126 mounted upon the pedestal 6. This arm 124 is provided therethrough with an opening 127 to register with the openings 128 in the arms of the bracket

126 to permit a cotter pin 129 or the like to be inserted through the said registering openings 127 and 128 when the member or head 115 is so placed as to have the trip block 40 in running position with respect to the rollers 39 for the valves 37.

When the trip block 40 is in running position, the contact arm 33 is in a position to avoid contact with the rollers 32 associated with the air starting valves 30. The arm 124 is provided with an upstanding hand-grasp 130 whereby, with the cotter pin 129 removed, the member or head 115 may be readily swung or moved in position to bring the contact arm 33 in place to be contacted by the rollers 32 and at the same time move the trip block 40 away into an ineffective position. This adjustment can be readily effected as it is employed upon the starting of the unit and at which time the rotor block R is stationary. After the rotor block R has rotated sufficiently to assure the desired ignition of the fuel charge, the member or head 115 is returned and locked in its first position with, of course, the trip block 40 in effective or working location.

While the unit as hereinbefore described has been particularly referred to as being employed in connection with an electrical generating means yet it is to be stated that it is within the concept of the invention to eliminate such generating means if desired and employ the engine to deliver power directly from the rotating parts, as, for example, from the take-off pulley 90.

It is believed to be clearly apparent from the foregoing that the power unit herein embodied eliminates the necessity of a fly wheel since the rotor block R, effectively serves as a fly wheel and assures the unit operating smoothly and in a non-pulsating manner. On the back or in-stroke of the pistons 63, the air remaining in the cylinders 17 is compressed to several hundred pounds pressure and with a corresponding temperature that will ignite the incoming fuel oil spray.

It is also to be pointed out that wherever required suitable packing will be provided as the requirements of practice may deem necessary.

From the foregoing description it is thought to be obvious that a power generating unit constructed in accordance with my invention is particularly well adapted for use by reason of the convenience and facility with which it may be assembled and operated.

I claim:

1. In a power unit comprising, a rotor, a tubular shaft therefor, cylinders carried by the rotor around the shaft and substantially parallel to the axis of the shaft and pistons reciprocating within the cylinders; means forming a driving connection between the pistons and rotor for effecting turning of the rotor and shaft, a manifold carried by and surrounding the shaft to one side of the rotor, normally closed tubular means connecting said manifold with each of the cylinders, a fuel line leading from a source of supply and extending within the shaft and leading to and having communication with the manifold, a second manifold rotating with the shaft, a line leading from a source of air under pressure and extending through the shaft to the second manifold, tubular connecting means between each of the cylinders and the second manifold, both of said connecting means being normally closed, and a means common to the two connecting means for selectively opening the connecting means between one manifold and the

cylinders when the means for opening the connecting means between the other manifold and the cylinders is closed.

2. In a power unit, a tubular shaft, a rotor mounted thereon for rotation therewith, bearings for the shaft, cylinders carried by the rotor around the shaft, pistons working in the cylinders, means operatively coupling the pistons with the rotor for turning the latter, a fuel manifold rotating with the shaft, means for admitting fuel from the manifold to the cylinders in timed sequence, a pipe line extending into the shaft lengthwise thereof and leading to the manifold, said pipe line extending outwardly beyond an end of the shaft, a fuel reservoir carried by a bearing with which the outer portion of the pipe line communicates, an air manifold rotating with the shaft, means for admitting air from the air manifold to the cylinders when the fuel admitting means is inoperative, a pipe line extending through the shaft and through the first pipe line and leading to the air manifold, and an air pressure reservoir carried by a bearing with which the second named pipe line communicates.

3. In a power unit, a tubular shaft, a rotor mounted thereon for rotation therewith, bearings for the shaft, cylinders carried by the rotor around the shaft, pistons working in the cylinders, means operatively coupling the pistons with the rotor for turning the latter, a fuel manifold rotating with the shaft, means for admitting fuel from the manifold to the cylinders in timed sequence, a pipe line extending into the shaft lengthwise thereof and leading to the manifold, said pipe line extending outwardly beyond an end of the shaft, a fuel reservoir carried by a bearing with which the outer portion of the pipe line communicates, an air manifold rotating with the shaft, means for admitting air from the air manifold to the cylinders when the fuel admitting means is inoperative, a pipe line extending through the shaft and through the first pipe line and leading to the air manifold, an air pressure reservoir carried by a bearing with which the second named pipe line communicates, a water jacket surrounding each of said cylinders, a water conducting pipe within the shaft and surrounding the major portions of the pipe lines therein for conducting water into the jackets, and means spacing said water conducting pipe from the encasing shaft, the space between said water conducting pipe and the shaft providing means for conducting water away from said jackets.

4. In a power unit, a tubular shaft, a rotor mounted thereon for rotation therewith, bearings for the shaft, cylinders carried by the rotor around the shaft, pistons working in the cylinders, means operatively coupling the pistons with the rotor for turning the latter, a fuel manifold rotating with the shaft, means for admitting fuel from the manifold to the cylinders in timed sequence, a pipe line extending into the shaft lengthwise thereof and leading to the manifold, said pipe line extending outwardly beyond an end of the shaft, a fuel reservoir carried by a bearing with which the outer portion of the pipe line communicates, an air manifold rotating with the shaft, means for admitting air from the air manifold to the cylinders when the fuel admitting means is inoperative, a pipe line extending through the shaft and through the first pipe line and leading to the air manifold, an air pressure reservoir carried by a bearing with which the second named pipe line communicates, and a water jacket within the shaft and surrounding the major portions of the

pipe lines therein, the rotor having water circulating passages in communication with the water jacket and with the space between the water jacket and the inner wall of the shaft.

5. In a power unit, a rotor body, cylinders carried by the rotor body at points spaced there-around and disposed substantially parallel to the axis of the rotor body, pistons working in the cylinders, operative connections between the pistons and the rotor body for effecting turning of the body, fuel lines delivering to the cylinders, normally closed valves for said lines, air pressure lines delivering to the cylinders, normally closed valves for said air lines, said lines and valves rotating with the rotor, the valves for the fuel lines being radially spaced with respect to the valves for the air lines, both sets of valves having operating stems extending exteriorly of the lines, a movable member supported adjacent to the outer ends of the stems of the valves, means carried by said movable member when said member is in one position for coaction with the stems of the valves in the fuel lines for successively opening said valves as the rotor body rotates, and means carried by said movable member for coaction with the stems of the valves of the air lines for opening such valves when the member is in a second position.

6. In a power unit, a rotor body, cylinders carried by the rotor body at points spaced there-around and disposed substantially parallel to the axis of the rotor body, pistons working in the cylinders, operative connections between the pistons and rotor body for effecting turning of the body, fuel lines delivering to the cylinders, normally closed valves for said lines, air pressure lines delivering to the cylinders, normally closed valves for said air lines, said lines and valves rotating with the rotor, the valves for the fuel lines being radially spaced with respect to the valves for the air lines, both sets of valves having operating stems extending exteriorly of the lines, a movable member supported adjacent to the outer ends of the stems of the valves, means carried by said movable member when said member is in one position for coaction with the stems of the valves in the fuel lines for successively opening said valves as the rotor body rotates, and means carried by said movable member for coaction with the stems of the valves of the air lines for opening such valves when the member is in a second position, said last named means being ineffective when the first named means is effective and vice versa.

7. In a power unit, a rotor body, cylinders carried by the rotor body at points spaced there-around and disposed substantially parallel to the axis of the rotor body, pistons working in the cylinders, operative connections between the pistons and the rotor body for effecting turning of the body, fuel lines delivering to the cylinders, normally closed valves for said lines, air pressure lines delivering to the cylinders, normally closed valves for said air lines, said lines and valves rotating with the rotor, the valves for the fuel lines being radially spaced with respect to the valves for the air lines, both sets of valves having operating stems extending exteriorly of the lines, a movable member supported adjacent to the outer ends of the stems of the valves, means carried by said movable member when said member is in one position for coaction with the stems of the valves in the fuel lines for successively opening said valves as the rotor body rotates, and

means carried by said movable member for coaction with the stems of the valves of the air lines for opening such valves when the member is in a second position, the means for opening the valves of the air lines, when effective, maintaining open at the same time a plurality of such valves.
